William C. Dajnowicz, Detroit, Mich., assignor to Valor Tool and Machine Co., Dearborn, Mich.,
a corporation of Michigan

Application July 13, 1949, Serial No. 3,891

Term of patent 14 years

(Cl. D74—1)

To all whom it may concern:

Be it known that I, William C. Dajnowicz, a citizen of the United States of America, residing at Detroit, in the county of Wayne, State of Michigan, have invented a new, original, and ornamental Design for a Combination Desk Letter Holder and Letter Opener, of which the following is a specification, reference being had to the accompanying drawing, forming a part thereof.

In the drawing:

Figure 1 is a front elevational view of a combination desk letter holder and letter opener showing my new design;

Fig. 2 is a top plan view of the design shown in Fig. 1;

Fig. 3 is a side elevational view of the design shown in Fig. 1, taken from the left-hand end thereof; and

Fig. 4 is a rear elevational view of the design shown in Fig. 1.

I claim:

The ornamental design for a combination desk letter holder and letter opener, as shown.

WILLIAM C. DAJNOWICZ.
